GAMEBOARD AND PLAYING CARDS

Marie L. McKeever, Jacksonville, Fla.

Application October 12, 1950, Serial No. 189,803

5 Claims. (Cl. 273—135)

The present invention relates to improvements in gameboards and cards, and more particularly to a gameboard and set of playing cards which is particularly adapted for use in playing a first game which I call "Rhombola" and a second game which I call "Congo." The board upon which the games may be played is called a "Congo Board," and the cards are designated "Bombay Cards."

An object of the present invention is to provide a novel gameboard upon which novel games may be played and which will provide amusement to the participants.

It is a further object of the present invention to provide a gameboard and set of cards which may be employed in conjunction with a set of rules to provide a game which is interesting and requires skill and knowledge of the rules.

Various other objects will become apparent from the detailed description to follow.

The best form in which I have contemplated applying my invention is clearly illustrated in the accompanying drawings, wherein:

Figure 1 is a view of my playing cards showing the major cards of each of the four sets;

Figure 2 is a top plan view of the gameboard of the present invention; and

Figure 3 is a vertical longitudinal sectional view taken substantially along the plane of line 3—3 of Figure 2.

Referring more particularly to the drawings, wherein like numerals designate like parts throughout, the numeral 10 designates generally a set of playing cards, while the numeral 12 designates generally the gameboard which is adapted to be employed in conjunction with the set of game cards to provide a novel game.

The gameboard 12 is comprised of a substantially rectangular board 14 having a central rectangular portion 16 of the board designating a "punch bowl" playing area. The "punch bowl" playing area is outlined with grooves 18 which extend the entire length of the board 14. Transversely extending grooves 20 complete the outline of the central rectangular portion 16. Indicia markings 22 may be provided for designating the area as the "punch bowl."

A pair of playing sections 23 and 24 are disposed on each side of the central portion 16 and have inlaid indicia 26 formed therein for designating the sections as "pool" sections. Grooves 28, 30 and 32 define the ends of the sections 23 and 24.

The corner playing areas 34, 36, 38 and 40 of the board 14 are positioned at the diagonal extremities of the central portion 16 and are outlined with the grooves 18, 26, 28 and 32. The corner playing areas are of rectangular form.

A plurality of transversely extending grooves 46 and 48 and a plurality of vertically extending grooves 42 and 44 form squares 50 out of the area between the pair of corner playing areas 34 and 40. The area between the opposite pair of corner playing areas 36 and 38 is divided into a plurality of non-rectangular areas

2

52 and 54 which have grooved indicia markings thereon designating various numerical values.

10 The corner playing areas 34 through 40 are divided into a pair of triangular sections 56 and 58 which overlap each other to provide a central diamond area 60. Each of the triangular sections 56 and 58 is provided with numerical indicia 62. Each of the corner playing areas is provided with a numerical indicia different from that of any of the other corner playing areas, and each of the numerical indicia in the same corner playing area is of a color different from the other numerical indicia.

15 In the diamond area 60, a pair of "positive" indicia markings 64 are provided which are of different colors.

The game cards 10 consist of four sets 70, 72, 74 and 76, each set consisting of twelve cards. The entire pack of cards 10 consists of two suits of cards of twenty-four cards each, and one suit is known as the "blue" suit, while the other is known as the "red" suit. The sets 74 and 76 are the blue suit, while the sets 70 and 72 are the red suit. The red suit consists of two branches 70 and 72 of twelve cards each, the set 70 being the "minus" branch, and the set 72 being the "plus" branch.

20 The "blue" suit is the major suit, consisting of twelve plus cards with the blue plus sign thereon, and known as the "blue plus branch." The blue suit also comprises twelve minus cards with the blue minus sign thereon, and known as the "blue minus branch."

25 The "red" suit is known as the minor suit, and comprises twelve plus cards with the red plus sign thereon, which are known as the "red plus branch." The red suit also includes twelve minus cards with the red minus sign thereon, and is known as the "red minus branch." The twelve cards in each branch are numbered from 1 through 10, 20 and 25. The three highest ranking cards of each branch are designated by particular symbols.

30 The "red" and "blue" plus branches of the numerical values 10, 20 and 25 bear the clasped hands, the lambs and the doves, respectively. The "red" and "blue" minus branches of the values 10, 20 and 25 bear the fighting fists, the lions and the dragons, respectively.

35 40 One such game that may be played with the gameboard and game cards of the present invention is as follows:

Rhombola

PLAYING THE GAME

45 Rhombola may be played by any number of persons from four to twelve. Players cut for first deal. The person who cuts the highest plus card deals first. In cutting for deal, minus cards do not count. When two persons cut high cards of the same numerical value, as +9 Blue, and +9 Red, the Blue is the high card because Blue is the major suit. The dealer first shuffles the deck thoroughly. After cards have been shuffled, the player at the 50 dealer's right cuts the deck. The dealer, beginning at his 55 left, deals the cards one at a time until the entire deck has been dealt.

THE PAY-OFF #1

60 50 Pay-off, number one, considers only the two ends of the board. The dealer calls for the pay-off. Then the players who hold minus cards in the Red Suit must pay off by placing on the board as many tokens as shown by the numerical value of the Minus Red (only) cards in his hand. The tokens are placed on the board in the sections corresponding to his pay-off cards. In pay-off #1, only those players who hold Minus Red cards are required to pay.

65 55 Example.—The player who holds —10 Red places 10 tokens in section number 10 at the end of the board. If he also holds other minus red cards, as —5 Red and —1 Red, he also places 5 tokens in section 5 and 1 token in

section 1. All other players holding minus cards in red follow in like manner.

PAY-OFF #2

Pay-off number 2 deals only with corners. The dealer calls for pay-off to corners. The players who hold minus cards in Blue corresponding to the numbers of the corners, that is, 9, 10, 20, and 25, must place an equal number of tokens in the corresponding corners.

Example.—The player who holds —25 Blue, places 25 tokens in the "25" corner. The player who holds —20 Blue, places 20 tokens in the "20" corner. The players who hold —10 Blue and —9 Blue follow in like manner.

PAY-OFF #3

Pay-off number three deals only with the Punch Bowl. Beginning with the dealer, each player places an equal number of tokens in the punch bowl. They may place one, two, three, or as many as agreed upon by the players. However, each and every player must contribute the same amount. The amount is agreed upon at the beginning of the game, before the first card is dealt.

COLLECTIONS

After all sections have been properly covered, and each player has contributed to Punch Bowl, the dealer calls.

COLLECTION #1 (Use the Punch Scale)

Tokens in the punch bowl are collected in the following manner. The challenge begins with the dealer. If he has a punch combination, he challenges by offering a sum of chips, one or more, as a challenge against anyone who thinks he has a stronger punch hand. The challenge goes around from the dealer's left. Each player has a chance to enter into the bidding. If a player wants to accept the challenge when it gets to him, he says "I accept." As the challenge proceeds around the board, a player may raise the previous bid if he has a punch combination which he thinks is better. A player who does not hold a punch combination may drop out by saying "Nullo." The challenge goes around and around. It stops when two or more players agree to a challenge, and there are no further raises.

The raising of a challenge shall stop before all other players become nullo. There must be two or more to meet a challenge.

The one and only time one player may take all the tokens in the punch bowl without a challenger, is when the original challenger does not get a competitor. He then takes all the chips in the punch bowl without question or exposing his hand.

The players who have dropped out by saying "Nullo" do not add any tokens to the punch bowl. Only those who stay in the bidding and meet the final challenge are required to put the amount bid in the punch bowl. The hands are then exposed. The player who holds the highest punch combination gets all the tokens in the punch bowl. (Use Punch Scale to determine the highest punch hand.)

SPECIAL NOTE ON PUNCH

After the bidding has started, when a player raises a bid, then all other players say "Nullo," leaving only one challenger without a competitor, and the bidding drops back to where it was before the last raise. Then the last "Nulls" will be compelled to agree to the last bid accepted.

Example.—We'll say that twelve people are playing. Six players have dropped out by saying "Nullo" when the bidding reached 45. Now, a player whom we shall call "G" raises the bid to 50. Then players "H," "I," "J," and "K" all say "Accept," meaning that they meet the challenge of 50. But player "L" raises to 55. Then players "G," "H," "I," "J," and "K" all say "Nullo." The five nulls void the arise of 55 and the bid drops back to 50. "L" is compelled to accept 50 together with "G,"

"H," "I," "J" and "K." Each puts 50 tokens in the punch bowl. The highest punch combination (see punch scale) wins all the tokens in the punch bowl.

NOTE ON PUNCH

5 The highest bidder cannot raise his own challenge after it has been accepted with no further raises by other players.

SECOND COLLECTION

(Collecting from the end sections)

10 The dealer calls for end collections meaning that all players who hold blue "Naturals" shall collect. (A Natural is any two cards of the same suit, and same numerical value; one Plus and the other Minus.) Any such combination as +4 Blue with —4 Blue or +25 Red with —25 Red are called Naturals. Any player holding a Blue Natural (Blue only) shall collect all the tokens in the sections at either end of the board where the number corresponds with the Blue Natural in his hand.

15 *Example.*—When a player holds a 4-natural in blue, meaning +4 Blue with —4 Blue (a natural), he shall collect all the tokens from section 4. The player who holds +25 Blue with —25 Blue (a natural) shall connect all the tokens in section 25 at the end of the board. The same applies to all the sections at the two ends of the board. Note: Some uncollected tokens will often be left in some of the end sections. They shall remain there and build up deal after deal until collected.

30 COLLECTING CORNERS

The player who holds the square of either of the four numbers in the corners shall collect all the tokens in the corner where the number corresponds to the four cards in his hand. (A Square is any four card combination of equal numerical value, one from each of the four branches, as "+8 Blue, —8 Blue, +8 Red, —8 Red." Any such combination is a Square.

35 The player who holds the 25-Square "+25 Blue, —25 Blue, +25 Red, —25 Red," shall collect all the tokens in the "25" corner. The same applies to the other three corners, 9, 10, and 20. When no player holds a square, and the corners cannot be collected, the dealer shifts the tokens from the corners to the adjoining pools. The pools will grow after each deal when the corners are not collected.

PLAYING FOR THE POOLS

The game ends after each player has dealt an equal number of times, once, twice, or as many times as agreed 40 upon. In playing for the tokens in the pools, cards shall be discarded to the punch bowl until four persons have discarded all their cards. The first person who discards all his cards gets all the tokens in the largest pool. The second person who discards all his cards gets all the tokens from the next smaller pool. The third and fourth persons to discard get the tokens from the next two smaller pools. If all the pools contain the same amount, either pool may be taken.

PLAYING POOL

The discard is done in the following manner: The dealer begins by discarding to the punch bowl the lowest card in his hand in any suit, any branch, but it must be the lowest card in his hand. The discard shall continue consecutively (in numerical order) until four cards of the same branch have been discarded. The dealer keeps the punch bowl clean after each four cards have been played. The person who plays the last of the four cards shall begin the next discard in a different branch. Each time a discard is made, the player must call the name of the card. The discard shall Always Be Done In Fours.

Illustrations.—When the leading discard is Blue +8, it shall be followed by Blue +9, Blue +10, Blue +20. The player who discards Blue +20 shall make the next lead

in a different branch, as Blue -1 which is followed by Blue -2, Blue -3, Blue -4. The player who discards Blue -4 makes the next lead. When four consecutive cards cannot be discarded for the reason that the next higher card in sequence has been played, or because the discard started high, then the sequence shall break at three cards, two cards, or one card. However, in each case, the person playing the last card in the four-run shall begin the next discard.

Illustration.—The player whom we shall call "G" makes a lead by discarding Blue -3. Blue -4 has already been discarded; therefore no player can follow in sequence. In a case like this, when a discard cannot be followed in sequence, the player makes another discard in a different branch. So, "G" makes another discard, playing the lowest card in another branch. "G" discards Red -25 which is the lowest card he holds in the Red Minus branch. Since -25 is the highest card in the branch, no player can follow. Therefore "G" has still another chance to discard. He then discards Red +2. He also holds Red +3, which he discards. "G" has discarded four cards. This completes the four-run.

Since "G" played the last card in the four-run, he himself makes the next lead, if he can change branches. (If "G" cannot change branches, the lead passes to the first player on the left of "G" who can change branches, meaning a branch different from the last one played by "G" which was Red Plus branch.) However, "G" can change branches; therefore he does make the next lead. He plays Blue -6. Another player whom we shall call "H" discards Blue -7. Blue -8 has already been discarded, so "H" discards Red -3. "B" discards Red -4. This completes the four-run. "B" who played the last card in the four-run makes the next lead, in a different branch.

Note.—The same rule applies when a player discards four consecutive cards, as Red +1, Red +2, Red +3, Red +4. The four-run is completed and since he played the last card in the four-run, he has a chance to make another lead, in a different branch. The first player who discards all his cards lets it be known by saying "Pool." He wins all the chips in the largest pool. The discard continues until four persons have discarded all their cards, winning the chips in the pools from the largest to the smallest.

Uncollected tokens which have accumulated in the end sections shall be pooled off in the same manner. Before pooling off the end sections, the cards must be well shuffled before dealing.

The winner of the game is the one who collects the most chips or tokens over the amount he put in the game.

Punch scale

1. Square: Any four cards of equal value, one from each of the four branches, as Blue -20, Blue +20, Red -20, Red +20
2. Quartet: Any four cards of the same branch running consecutively, as Blue -8, Blue -9, Blue -10, Blue -20 or Red +1, Red +2, Red +3, Red +4
3. Triangle: Any three cards of the same branch, when the total of two equals the third, as Red +3, Red +4, Red +7 or Blue -5, Blue -3, Blue -8
4. Trio: Any three cards of the same branch running consecutively, as Red -7, Red -8, Red -9 or Blue +9, Blue +10, Blue +20
5. Natural: Any two cards having the same numerical value, and the same suit, one plus—the other minus, as Red -10, Red +10 or Blue -3, Blue +3
6. Duet: Any two consecutive cards of the same branch, as Blue -6, Blue -7 or Red +10, Red +20
7. Solo: The highest single card

Note.—In determining the value of a punch hand.

- (1) When two hands are on the same scale and have the same numerical value but different suits, as Blue -5,

Blue -6, Blue -7, Blue -8 and Red +5, Red +6, Red +7, Red +8

Blue is always the higher.

- 5 (2) When two hands on the same scale have the same numerical value and same suit but different branches, as Blue +5, Blue +6, Blue +7, Blue +8, and Blue -5, Blue -6, Blue -7, Blue -8.

The plus branch is the higher hand of the two.

Another such game is described as follows:

Congo

PLAYING THE GAME

15 Congo may be played by any number of persons from 6 to 12. However, 8 makes a good game. Players cut for deal. The player cutting the highest plus card gets the first deal. Minus cards do not count in cutting for deal. If two persons cut high cards of the same value, as plus 8 blue and plus 8 red, the blue is the higher. (Blue is always the higher ranking suit.) The deal then rotates until each player has dealt. Cards must be well shuffled before each deal.

MASTER SUIT

20 The first step in playing the game is to determine which shall be the master suit, the Red or the Blue. The player at the dealer's right cuts the deck of cards. The Red or Blue suit, whichever turns up when the cards are cut, becomes the master suit. This master is the suit which controls the pay-off and collection. The deal begins at the dealer's left and continues around until all cards have been dealt.

PAY CARDS

25 After all cards have been dealt, the dealer calls for the Pay-off. This means that each player who holds in his hand a minus card of the master suit must pay-off.

PAY-OFF #1

30 Players place as many chips on the board as indicated by the numbers on the minus cards of the master suit in his hand. Each player places his chips in the sections corresponding to the minus cards in his hand.

35 *Illustration.*—When Red has been cut for the master suit, the player who holds minus 8 in the Red Suit places 8 chips on the board in section 8. The player who holds minus 1 in Red places one chip on the board in section 1. The player who holds Minus 20 in Red places 20 chips on the board in section 20. If a person holds (in Red) several minus cards, as Minus 2, Minus 3 and Minus 5, he will place 2, 3, and 5 chips on the board in sections 2, 3 and 5. All players who hold minus cards of the master suit following the same manner until all the sections at the two ends of the board—1, 2, 3, 4, 5, 6, 7, 8, 9, 10, 20, and 25, have been properly covered.

PAY-OFF #2

40 Beginning with the dealer and going around toward his left, each and every player puts one chip in each of the four corners and one chip in the punch bowl.

COLLECTING

45 After all sections have been properly covered, and each player has placed one chip in each of the four corners, and one chip in the Punch Bowl, the dealer calls.

COLLECTION #1 (Use the Punch Scale)

50 Tokens in the Punch Bowl are punched off. Punch is collected by challenge. The challenge begins with the dealer. If he has a punch combination, he challenges by offering a sum of chips, one or more, as a challenge against anyone who thinks he has a stronger punch hand. The challenge goes around from the dealer's left. Each player has a chance to enter into the bidding. If a player wants to accept the last challenge made, he says "I Accept." As the challenge proceeds around the board,

a player may raise the previous bid if he has a punch combination which may be better. A player who does not hold a punch combination may drop out by saying "Nullo."

The challenge goes round and round, stopping when two or more players agree to a challenge and there are no further raises.

The raising of a challenge shall never continue until all other players become "Nullo." There must be two or more to meet a challenge.

The one and only time one player may take all the tokens in the punch bowl without a challenger is when the original challenger does not get a competitor. He then takes all the chips from the punch bowl without question or exposing his hand.

Those players who have dropped out by saying "Nullo" do not add any chips to the punch bowl. Only those who stay in the bidding and meet the final challenge are required to put the amount bid in the Punch Bowl. The punch hands are then exposed. The player who has the highest hand gets all the tokens from the Punch Bowl (Use Punch Scale).

Special note on Punch.—After the bidding has started, when a player raises a bid and all other players say "Nullo," leaving only the one challenger without a competitor, the bidding drops to where it was before the last raise. Then the last "Nullos" will be compelled to agree to the last bid accepted. Example: We'll say that 12 people are playing. Six players have dropped out by saying "Nullo" when the bidding reached 45. Now player "G" raises the bid to 50. Then players "H," "I," "J," "K" all say "Accept," meaning that they meet the challenge of 50. But player "L" raises to 55. Then players "G," "H," "I," "J," and "K" all say "Nullo." These five nullos void the raise of 55 and the bid drops to 50. The last challengers "G," "H," "I," "J," "K" and "L" must accept and each puts 50 tokens in the bowl. The highest Punch combination (See Punch scale) wins all the tokens in the Punch Bowl.

Note.—The highest bidder cannot raise his own challenge after it has been accepted, with no further raises by other players.

SECOND COLLECTION

The dealer calls for the plus cards of the master suit by ordering each person to make his claim. All players who hold plus cards of the master suit must show them. Then the dealer delivers the chips from the board to each person who holds a plus card of the master suit. Each player is given chips from the board from the sections corresponding to the numbers on the plus cards in his hand in the master suit.

Illustration.—When Red is the master suit, the player who holds plus (+) 1 red shows it and receives the chip from the board in section 1. The player who holds plus (+) 20 shows it and receives the chips from the board in section 20. All other players who hold plus (+) cards in the master suit follow in like manner until all the chips have been delivered from the board except the corners.

WHAT TO DO ABOUT CORNERS

The chips in the corners are collected by persons holding the two plus cards corresponding to the figures shown in the corners. Illustration: When a player holds in his hand plus (+) 9 Blue, also plus (+) 9 Red, he collects the chips from the "9" corner. The player who holds +20 Red also +20 Blue collects the chips from the "20" corner. The same applies to the other corners—10 and 25. However, when no player holds the two plus cards corresponding to the corners, the chips in the corners which are unclaimed are shifted to the adjoining pools by the dealer. The shifting of the chips from the corners to the pools is done after each collection. The pools will often grow until the end of the game.

PLAYING FOR THE POOLS

After the players have dealt an equal number of times, once, twice or as many times as agreed upon by the players, the game is ended by playing off the pools, in the following manner. Beginning with the dealer, cards shall be played to the Punch Bowl until four persons have discarded all their cards. The first person who discards all his cards gets all the chips in the largest pool. The second person who discards all his cards gets all the chips from the next smaller pool. The third and fourth persons collect the next two smaller pools. If all pools contain the same amount, either pool may be taken by the first to discard.

15

PLAYING POOL

The discard is done in the following manner: The dealer begins by discarding to the Punch Bowl the lowest card in his hand in the master suit. The discard may be made from either branch (plus or minus). If the dealer does not hold a card in the master suit, then the first person on his left who does hold a card in the master suit shall begin the discard by playing the lowest. The discard shall continue consecutively (in numerical order) until four cards of the same branch have been played.

20 The dealer keeps the Punch Bowl clean after each four cards have been played. The person who plays the last of the four cards shall begin the next discard in a different branch. Each time a discard is made the player must call the name of the card. The discard shall always be done in fours.

25 *Illustration.*—When the leading discard is +8 Blue, it shall be followed by +9 Blue, +10 Blue, +20 Blue. The player who discards +20 Blue shall make the next lead with a change of branch, as —1 Blue, which is followed by —2 Blue, —3 Blue, —4 Blue. The player who discards —4 Blue makes the next lead. When four consecutive cards cannot be discarded for the reason that the higher card has been played, or because the discard started high, then the sequence shall break at three cards, 30 two cards, or one card. However, in each case the person playing the last card in the four shall begin the next discard.

35 *Illustration.*—The player whom we shall call "G" makes a lead by discarding —3 Blue. —4 Blue has already been discarded. Therefore "G" makes another discard, playing the lowest card in another branch. The player "G" discards —25 Red which is the lowest card he holds in his hand in the Minus Red branch. Since —25 is the highest card in the branch, no player can follow. Therefore "G" has another chance to discard. He then discards +2 Red. He also holds +3 Red which he discards. "G" has discarded four cards. This completes the four-run.

40 In view of the fact that "G" played the last card in the four-run, he himself makes the next lead, if he can change branches. (If "G" cannot change branches, the lead passes to the first player on the left of "G," who can change branches, meaning a different branch from the last one played by "G" which was the +Red branch).

45 45 However, "G" can change branches. Therefore, he does make the next lead, playing —6 Blue. Another player whom we shall call "H" discards —7 Blue. —8 Blue has already been discarded, so "H" discards again. He discards —3 Red. "B" discards —4 Red. This completes the four-run. "B," the last player in the four-run makes the next lead and changes branches from —Red.

50 *Note.*—The same rule applies when a player discards four consecutive cards, as +1 Red, +2 Red, +3 Red, +4 Red. The four-run is discarded by one person and he has 55 a chance to make another lead, provided he can change branches. The first player who discards all his cards lets it be known by saying "Pool." He wins all the chips in the largest pool. The discard continues until four persons have discarded all their cards, winning the chips 60 in the pools from the largest to the smallest.

The winner of the game is the player who collects the most chips over the amount he put in the game.

Note.—When a player wins a pool, the next lead is made by the first player on his left. The First (only the first) card played after a pool is won may or may not be played from a different branch.

Having described the invention, what is claimed as new is:

1. A gameboard comprising a substantially rectangular board, a central rectangular portion of said board designating a "Punch Bowl" playing area and outlined with grooves in said board, a pair of playing sections disposed on each side of said central portion and having inlaid indicia therein designating the sections as "Pool" sections, opposite pairs of corner playing areas on said board positioned at the diagonal extremities of said central portion and outlined with grooves forming continuations of the outlining grooves of said central portion, and a plurality of grooves forming squares out of the area between a pair of corner playing areas, the area between the opposite pair of corner playing areas being divided into a plurality of non-rectangular areas having indicia markings thereon of various numerical values, and a deck of game cards for use with a gameboard of the type described comprising a multiplicity of cards of a plurality of sets, each set containing the same number of cards, each set of cards having numerical indicia of various consecutive values and of the same values as the numerical indicia of the gameboard, and each set of cards being of a color different from that of another set.

2. A gameboard comprising a substantially rectangular board, a central rectangular portion of said board designating a "Punch Bowl" playing area and outlined with grooves in said board, a pair of playing sections disposed on each side of said central portion and having inlaid indicia therein designating the sections as "Pool" sections, opposite pairs of corner playing areas on said board positioned at the diagonal extremities of said central portion and outlined with grooves forming continuations of the outlining grooves of said central portion, and a plurality of grooves forming squares out of the area between a pair of corner playing areas, the area between the opposite pair of corner playing areas being divided into a plurality of non-rectangular areas having indicia markings thereon of various numerical values, said corner playing areas all being provided with numerical indicia of different denominations, and a deck of game cards for use with a gameboard of the type described comprising a multiplicity of cards of a plurality of sets, each set containing the same number of cards, each set of cards having numerical indicia of various consecutive values and of the same values as the numerical indicia of the gameboard, and each set of cards being of a color different from that of another set.

3. A gameboard comprising a substantially rectangular board, a central rectangular portion of said board designating a "Punch Bowl" playing area and outlined with grooves in said board, a pair of playing sections disposed on each side of said central portion and having inlaid indicia therein designating the sections as "Pool" sections, opposite pairs of corner playing areas on said board positioned at the diagonal extremities of said central portion and outlined with grooves forming continuations of the outlining grooves of said central portion, and a plurality of grooves forming squares out of the area between a pair of corner playing areas, the area between the opposite pair of corner playing areas being divided into a plurality of non-rectangular areas having indicia markings thereon of various numerical values, said corner playing areas all being provided with numerical indicia of different denominations, each of said corner playing areas being divided into two sections each having indicia designating "Positive" values, and each of said "Positive" values in the same area being of a different color, and a deck of game cards for use with a gameboard of the type described

comprising a multiplicity of cards of a plurality of sets, each set containing the same number of cards, each set of cards having numerical indicia of various consecutive values and of the same values as the numerical indicia of the gameboard, and each set of cards being of a color different from that of another set.

4. A gameboard comprising a substantially rectangular board, a central rectangular portion of said board designating a "Punch Bowl" playing area and outlined with grooves in said board, a pair of playing sections disposed on each side of said central portion and having inlaid indicia therein designating the sections as "Pool" sections, opposite pairs of corner playing areas on said board positioned at the diagonal extremities of said central portion and outlined with grooves forming continuations of the outlining grooves of said central portion, and a plurality of grooves forming squares out of the area between a pair of corner playing areas, the area between the opposite pair of corner playing areas being divided into a plurality of non-rectangular areas having indicia markings thereon of various numerical values, and a deck of game cards for use with a gameboard of the type described comprising a multiplicity of cards of a plurality of sets, each set containing the same number of cards, each set of cards having numerical indicia of various consecutive values and of the same values as the numerical indicia of the gameboard, and each set of cards being of a color different from that of another set, "Positive" indicia on a pair of sets, and "Negative" indicia on another pair of sets.

5. A gameboard comprising a substantially rectangular board, a central rectangular portion of said board designating a "Punch Bowl" playing area and outlined with grooves in said board, a pair of playing sections disposed on each side of said central portion and having inlaid indicia therein designating the sections as "Pool" sections, opposite pairs of corner playing areas on said board positioned at the diagonal extremities of said central portion and outlined with grooves forming continuations of the outlining grooves of said central portion, a plurality of grooves forming squares out of the area between a pair of corner playing areas, the area between the opposite pair of corner playing areas being divided into a plurality of non-rectangular areas having indicia markings thereon of various numerical values, said corner playing areas all being provided with numerical indicia of different denominations, each of said corner playing areas being divided into two sections each having indicia designating "Positive" values, and each of said "Positive" values in the same area being of a different color, and a deck of game cards for use with a gameboard of the type described comprising a multiplicity of cards of a plurality of sets, each set containing the same number of cards, each set of cards having numerical indicia of various consecutive values and of the same values as the numerical indicia of the gameboard, and each set of cards being of a color different from that of another set, "Positive" indicia on a pair of sets, and "Negative" indicia on another pair of sets.
